Primary Examiner — Sheryl Lane*Assistant Examiner* — Mark T. Philippss(74) *Attorney, Agent, or Firm* — STIP Law Group, LLC(57) **CLAIM**

The ornamental design for a machine center, as shown and described.

DESCRIPTION

FIG. 1 is a perspective view of the machine center, showing the present design.

FIG. 2 is a front view thereof.

FIG. 3 is a rear view thereof.

FIG. 4 is a left side view thereof.

FIG. 5 is a right side view thereof; and,

FIG. 6 is a top view thereof.

The broken lines in the figures are used to show portions of the machine center that form no part of the claimed design.
